[57] CLAIM

The ornamental design for a tennis teaching device,
substantially as shown and described.

DESCRIPTION

FIG. 1 is a front view of a tennis teaching device showing
my new design. The tennis ball holders are shown
fragmentarily and swung to the side for clarity;
FIG. 2 is a rear view of FIG. 1;

FIG. 3 is a left side view thereof;

FIG. 4 is a right side view thereof;

FIG. 5 is a top view thereof.

FIG. 5
